CLAIM

The ornamental design for a magnetic head car phone holder, as shown and described.

DESCRIPTION

FIG. 1 is a perspective view of my new design, showing a magnetic head car phone holder;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a third perspective view thereof, shown in an alternate position; and,

FIG. 10 is a fourth perspective view thereof, shown in the alternate position.

The line shading in FIGS. 1-10 represents contour and not surface ornamentation.

1 Claim, 10 Drawing Sheets
